CLEANING AND EXTRACTING MACHINE

Filed July 28, 1927

Fred L. Harding INVENTOR.

BY

Robt. D. Pearson

ATTORNEY.

Patented Nov. 13, 1928.

UNITED STATES PATENT OFFICE.

FRED L. HARDING, OF GLENDALE, CALIFORNIA.

CLEANING AND EXTRACTING MACHINE.

Application filed July 28, 1927. Serial No. 209,155.

This invention relates to clothes washing or cleaning machines and has for its object the provision of quickly adjustable mechanism whereby a reciprocating movement may be imparted to the clothes container during a washing process and a rotary or whirling motion may be imparted thereto to perform a drying operation.

The above and other objects of the invention will be more fully disclosed in the following specification and will be exemplified in the accompanying drawing, the single figure of which illustrates a vertical section through a washing machine embodying the invention.

In carrying out the invention 1 represents a tank or receptacle open at its top and provided with a cover 2. The cover 2 is preferably formed of sheet metal and is provided with a flange 3 which projects into the receptacle and has secured to its top surface a frame desirably a casting 4 provided with a centrally disposed bearing bore 5 and at its ends with suitable ears 6 and 7 which are adapted to engage with corresponding tongues 7' and 8 secured to the receptacle 1 to which the ears are pivoted by means of bolts 9 and 10.

The casting 4 is provided with an upwardly projecting standard 11 provided at its top with a bracket arm 12 having a bearing bore 13 formed therein which is in alignment with the bore 5 in the casting 4.

The arm 12 is provided with a stud shaft 14 upon which is journaled for rotation a bevel gear 15 having a bracket 16 formed thereon provided with a threaded bore for the reception of the threaded end of a stud 17 formed on a handle 18.

A vertically disposed shaft 19 is journaled in the bores or bearing 5 and 13 and secured on its lower end which projects into receptacle 1 is the cover 20 of a basket 21, said cover being hinged at 22 to said basket and adapted to be secured in place by means of a bolt 23 disposed opposite said hinge. The basket 21 and its top cover 20 is preferably formed of perforated metal in order that the liquid contained in the receptacle 1 may circulate therethrough and saturate the clothing therein.

Secured to the shaft 19 as by a set screw, is a pinion 24 adapted to be meshed with the gear 15, and pivoted at its upper end is a block 25 which is provided with a stud 26 to which the upper end of a link 27 is pivoted.

The link 27 is provided intermediate its ends with a bore 28 through which the stud

17 passes thus forming a link connection between the gear 15 and its crank 18 and the upper end of shaft 19.

The lower end 29 of link 27 projects downwardly below the top surface 30 of arm 12 and is provided with a threaded perforation 31 and the arm 12 is provided with an upstanding ear 32 also provided with a perforation for the reception of a cap screw 33.

The articles to be washed are placed in the basket 21 and the soapy water or other cleansing liquid placed in the tank 1. The crank 18 is then turned which through its link connection with the shaft 19 reciprocates the basket 21 upwardly and downwardly in the liquid contained in the tank.

When it is desired to dry the articles in basket 21, the link 27 is disengaged from the gear 15 by removing the handle 18 and is then swung around until the end 29 of said link rests upon the surface 30 of arm 12. The link is then secured to ear 32 by means of cap screw 33 as shown in dotted lines. During this operation the shaft 19 is lifted until the pinion 24 meshes with gear 15 and is held in its lifted position by the link 27 resting upon surface 30. The handle 18 is then again secured to the bracket 16 and upon turning the same the basket which has been lifted above the surface of the liquid will be caused to rotate, and thereby the articles therein will become drained and dried.

In order to insert the clothing in the basket 21, the bolt 10 is removed and the cover 2 is swung on the bolt 9 to a position shown in dotted lines and then the cover and the receptacle are swung apart.

Having thus described my invention what I claim is:

1. A washing machine comprising a tank; a receptacle mounted in said tank; a shaft journaled on said tank secured to said receptacle; a pinion fixed to said shaft; a gear journaled on said tank adapted to mesh with said pinion; a link pivoted to said shaft and to said gear; and a handle on said gear, said handle normally reciprocating said shaft while said gear and pinion are disengaged from each other, said gear and pinion being adapted to be brought into engagement with each other to rotate said shaft while the reciprocating function is rendered inoperative, and said link sustaining said pinion in mesh with said gear during the rotary operation of the aforementioned receptacle.

2. A washing machine comprising a tank; a receptacle mounted in said tank; a shaft journaled on said tank and secured to said receptacle; a bearing block on said shaft; a gear journaled on said tank; a pinion on said shaft adapted to mesh with said gear; a handle removably secured to said gear and a link pivoted to said bearing block and to said gear by means of said handle.
- 10 3. A washing machine comprising a tank; a receptacle mounted in said tank; a hinged cover for said tank; a normally upright shaft; a pinion mounted on said shaft to rotate therewith; a frame mounted upon said cover and having bearings for said shaft in vertically spaced relation to each other, said shaft being reciprocatory and rotatable in said bearings; a bevel gear mounted on said frame; means to normally rotate said bevel gear and at the same time to reciprocate said shaft, said reciprocatory means including a link normally attached to said gear and which is adapted to be detached therefrom and then positioned to sustain said pinion in engagement with said gear in order to provide for transmitting from said gear to said shaft a rotary movement only of the latter.
- 15 In testimony whereof I hereunto affix my signature.

FRED L. HARDING.
